UNITED STATES PATENT OFFICE

95,817

DESIGN FOR A REFRIGERATOR CABINET

Norman Bel Geddes, New York, and William I. Hamby, Great Neck, N. Y., assignors to Servel, Inc., New York, N. Y., a corporation of Delaware

Application February 23, 1935, Serial No. 55,590

Term of patent 14 years

To all whom it may concern:

Be it known, that we, Norman Bel Geddes, a citizen of the United States, residing at 136 East 79th Street, city of New York, in the county of New York and State of New York, and William I. Hamby, a citizen of the United States, residing at West Shore Road, Great Neck, in the county of Nassau and State of New York, have invented a new, original, and ornamental Design for a Refrigerator Cabinet, of which the following is a

specification, reference being had to the accompanying drawing, forming part thereof.

The figure is a perspective view of a refrigerator cabinet showing our design.

We claim:

The ornamental design for a refrigerator cabinet as shown.

NORMAN BEL GEDDES.
W. I. HAMBY.
